UNITED STATES PATENT OFFICE.

THOMAS C. SHEEHAN, OF UPPER MONTCLAIR, NEW JERSEY, ASSIGNOR TO WADE & BUTCHER CORPORATION, A CORPORATION OF NEW JERSEY.

KNIFE GRINDING.

Application filed December 6, 1924. Serial No. 754,418.

This invention relates to an improvement in knife grinding, and particularly to the grinding of table knives, although it may be employed in grinding the surfaces of other articles.

Customarily, the grinding of the surfaces of such articles as table knives has been effected by means of grinding wheels made of a hard abradant and rubbing against the surface to be ground. Such wheels are sometimes, though not always, used in conjunction with a cooling agent such as water to prevent overheating of the article during the grinding operation. The results attained by the use of grinding wheels have heretofore been considered more or less satisfactory in accordance with the degree of finish desired. When a mirror-like surface has been desired, it has heretofore been necessary to supplement the grinding operation by a tedious and expensive polishing operation, usually manually performed, which greatly increased the cost of the article.

It has now been discovered that certain abradants possess properties which may be utilized in the grinding of table knives and other articles by means of a new method and apparatus, the use of which results in the production of articles having a mirror-like finish at an extremely low cost, even below that of similar articles heretofore produced which lacked a mirror-like finish. Emery, for example, although its specific gravity is greater than that of water, when reduced to a powder, becomes what may be termed a flotative abradant; that is to say, the powdered emery will float or will remain in suspension in still water for a period which depends upon its degree of fineness. In fact, the degree of fineness of powdered emery, which cannot be measured by the ordinary screening method used for coarser emery, may be, and is, measured by the period during which it will remain flotative or in suspension in still water; and the period during which the abradant retains its flotative property may be extended indefinitely by agitating the water to keep the flotative abradant in motion in the water while any larger particles that may be present will sink and accumulate in the bottom of the pool of water.

Although this flotative property of abradant has long been known, the only use, of

which I am aware, to which it has been put, is in the grading of the finer abradant powders, as above indicated.

The main object of the present invention is the production of a grinding method and apparatus wherein this flotative property of abradants is utilized to obtain superior results at a greatly reduced cost. Another object of the invention is the production of a machine in which such a method is employed, and which operates automatically and without the employment of skilled labor, to still further reduce the cost of producing the articles ground. With these and other objects not specifically mentioned in view, the invention resides in certain methods, apparatus and machines which will be herein-after fully described and then specifically set forth in the claims hereunto appended.

In the accompanying drawings, which form a part of this specification and in which like characters of reference indicate the same or like parts, Fig. 1 is a side elevation, partly in section, of a machine constructed in accordance with the invention; Fig. 2 is a detail front elevation of a part of the structure shown in Fig. 1, the part being indicated by the broken line 2-2 in Fig. 1; Fig. 3 is a cross-sectional view taken on the line 3-3 in Fig. 2; and Fig. 4 is a detail plan view taken on the line 4-4 in Fig. 1, the grinding member being indicated in dotted lines.

In carrying the invention into effect, there is provided a method of, and apparatus for, grinding a surface by producing a relative rubbing movement of said surface and of a relatively soft and inherently non-abrasive member, and simultaneously causing a liquid carrying a relatively small quantity of flotative abradant to pass between said surface and said member. In the best practice of the invention, the rubbing movement of the surface to be ground and of the operating surface of the relatively soft and inherently non-abrasive coating member occurs while the two surfaces are submerged in the liquid carrying the relatively small quantity of flotative abradant, and the abradant is caused to pass between the two surfaces by the flow of the liquid which is produced by the relative movement of the surfaces. In the best practice of the invention also, the grinding is effected in three stages, the

relative movement of the surface to be ground and of the coating member being different in each stage, in order to entirely eliminate all traces of marks made by the 5 abradant on the surface of the article in operation, so that the surfaces will have a mirror-like finish. In the best practice of the invention also, the pressure of the member against the surface to be ground differs 10 in the three grinding stages. For the initial stage, a mean effective pressure of 150 lbs. has been found to give the best results; while at the third stage, a mean effective pressure of only 2 lbs. has been found to 15 give the best results. For grinding some articles which do not require a high finish, the first stage of the present method is sufficient to accomplish the end sought; for grinding articles of another class which require a better finish than the articles just 20 mentioned, though not a mirror-like finish, the first two stages of the present method are necessary to accomplish the end sought; all three stages, however, are necessary to 25 the production of such articles as table knives having a mirror-like finish entirely free from any trace of abradant marks.

All the apparatus that is essential to practice of the invention in its simplest form is 30 a member of wood, or other inherently non-abrasive material, having an operating surface adapted to contact with the surface to be ground, and some means for causing a liquid carrying a relatively small quantity 35 of floatative abradant to pass between the surfaces; and the necessary rubbing movement may be manually produced. The abradant carrying liquid may be confined in a pool and caused to pass between said surfaces by means of the relative rubbing movement of the two surfaces. While the end sought can be accomplished by such manual practice of the invention, it is not the best way because it is not the most economical. 40 When used for knife grinding, one operator could grind only one blade at a time. By the use of the machine to be hereinafter described, however, one operator can grind 40 blades while the manual operator is grinding 45 one.

Referring to the drawings, which illustrate a machine—or rather one unit of a multiple unit machine—constructed in accordance with the invention, 5 indicates the 55 upper part of a pedestal carrying a bracket 6 at its side and a bed plate 7 at its top. Stationarily mounted in uprights 8 on the bracket 6 are two rollers 9—9, and resting upon these rollers is a carriage 10 surmounted by a support 12 for a pool 13 of liquid carrying a relatively small quantity 60 of floatative abradant and for a knife blade *k—b* submerged in said liquid. This pool is confined in a pan 14 formed integrally 65 with the support 12. The pan 14 has an

elevated bottom section 15, upon which the knife blade *k—b* rests. Inbuilt with this bottom section 15 is a magnetic chuck 16 of the type disclosed in my Patent No. 1,508,727, granted September 16, 1924. It is 70 adapted to twist the knife blade to cause it to present a flat surface to be ground. Normally contacting with the surface of the knife blade to be ground is an annular member 17 constructed of inherently non-abrasive material. Birch wood has been found to be peculiarly adapted for present purposes, although other non-abrasive material which is softer than the steel of the knife blade may be used. The member 17 is secured to a disk 18, screwed on a spindle 19 which is journaled in bearings 20—20 formed on a bracket 21. The bracket 21 is secured to the side of the upper bed plate 7 before referred to. The upper end of the 80 spindle 19 terminates in a flanged cup 22, and a helical spring 23 bears against the flange of the cup 22 and against a ball thrust bearing 24, which in turn bears against a collar 25 pinned to the spindle 19. 85 The cup 22 is centered in alignment with the axis of the spindle 19 by means of an adjustable centering screw 26 carried in the upper part 27 of the bed plate 7 before referred to. It will be understood that the 90 tendency of the spring 23 is to move the spindle 19 and member 17 downwardly to cause the latter to bear under pressure on the knife blade *k—b*.

Spined to the spindle 19 is a pulley 28, and overrunning this pulley is a belt 29 which also overruns a driving pulley 30, fast on a shaft 31, journaled in a bearing 32, carried by the bed plate 7. The shaft 31 carries a bevel gear 33 in mesh with and driven by a 100 bevel gear 34, the latter being fast on a shaft 35 which is the main power shaft of the machine and is journaled in bearings in the bed plate 7.

The power shaft 35 also carries a pulley 110 36 over which runs a belt 37 overrunning and driving a pulley 38 which is fast on a short shaft 39 journaled in the side of the pedestal 5. The shaft 39 carries a crank 40 which is connected to a link 41 which is also connected to the carriage 10 before referred to.

By the mechanism so far described, the member 17 is rotated at a given speed, and the support 12 is reciprocated at a slower speed, the mechanism for producing these 120 movements being interconnected. As the member 17 rotates, fine particles of abradant which are carried in suspension in the pool 13 are carried in between the operating surface of said member and the upper surface 125 of the knife blade *k—b*, the pool being agitated by the centrifugal force exerted by the whirling member 17. Simultaneously, the support 12, and of course the pool 13, and the knife blade, are given a relatively 130

slow reciprocating movement, so that the grinding effect is progressive along the knife blade.

- Mechanism is provided for disengaging 5 the member 17 from the knife blade *k-b*, while the direction of support reciprocation is changed at one end of the travel of the carriage 10 where the knife blade is thinnest, to avoid excessive grinding at this point 10 when the blade is temporarily stationary. This mechanism includes a cam block 42, fast on the block 11 before referred to, and therefore moving with it. It further includes a bell-crank 43-44, fulcrumed at 45 15 to the under side of the bed plate 7. The arm 43 of this bell-crank carried a roller 46, tracking on the top of the block 11 and coming into engagement with, and being lifted by, the cam 42 at one end of the support 20 reciprocation. As the bell-crank 43-44 is operated by the cam 42, its arm 44 engages the under side of, and lifts, a plunger 47 slideable in the bracket 21 before referred to. The upward movement of this plunger raises 25 a screw 48 which has a pin and slot connection with a lever 49, fulcrumed at 50 to the bracket 21, and having a pin 51 engaging a collar 52 on the spindle 19. Thus, the upward movement of the screw 48 lifts the 30 spindle 19, which in turn lifts the member 17 and disengages it from the knife blade and holds it in disengaged relation therewith until the roller 46 leaves the cam 42.

Means are provided for automatically adjusting the member 17 as it wears away. 35 This means includes the lifting mechanism just described, and another device. The screw 48 is provided with a ratchet head 53, engaged by a pawl 54, formed on a bell-crank 40 55-56, which is fulcrumed at 57, to the bracket 21. The arm 56 of the bell-crank 55-56 engages the lower end of the screw 48. When the spring 23 forces the spindle 19 downwardly as the member 17 slowly 45 wears away, the lever 49 is forced down with it; and this lever, through the action of its pin and slot connection at 58 with the screw 48, forces the latter downwardly, the screw 50 not being threaded in the bearings of the bracket 21 in which it is mounted. As the descending screw 48 presses against the short arm 56 of the bell-crank 55-56, the long arm 55, carrying the pawl 54, is given a movement which operates the ratchet 53 and turns 55 the screw 48. This action automatically readjusts the normal relative positions of the bell-crank 43-44, the lever 49, and the intermediate parts.

As the liquid carrying the floatative abrasive passes between the knife blade and the member 17, the fine particles of abradant are forced into the relatively soft material of said member until they are almost completely embedded therein. So embedded, they 60 move across the surface of the blade, yield-

ingly and therefore gently and slightly wearing away the steel in their respective paths. But when they have passed the blade, they are washed by the agitated liquid out of the beds they had made for themselves in said 70 member; and when they again reach a position between the blade and member, they become embedded in said member in new positions. Thus, the particles of abradant do not accumulate on the operating surface of the 75 member, but constantly change their positions, constantly presenting new patterns of particles to the blade and thereby avoiding the formation of the grooves and ridges in the blade surface which are inevitably produced by the same abradant when used in the 80 commercial solid wheel form.

The only duty the operator of the machine has to perform is to place a knife blade 85 in position on the magnetic chuck 16 before it is ground, and take it off when the grinding operation is finished. No skilled labor, therefore, is required in the operation of the machine.

The time required for the grinding operation, and the time required for the substitution of an unground knife blade for a ground knife blade in the machine, are such that one operator can keep in operation approximately 40 spindles, so that 40 blades 90 95 will be undergoing the grinding operation at the same time; and by placing blades successively on the 40 chucks, the machine can be kept in operation continuously. Although the drawings show but one spindle, 100 the commercial machine may have any number up to a maximum which is controlled by the rapidity with which an operator can substitute unground blades for ground blades; and the several units will all be 105 alike.

It will be recalled that in the machine shown and described, the relative rubbing movement of the blade and of the relatively soft and inherently non-abrasive member 110 which coacts therewith, is the resultant of a rotating movement of the member and a reciprocating movement of the blade, the former being rapid and the latter being slow.

While, as hereinbefore noted, the single 115 stage operation is sufficient for some purposes, it does leave visible abradant marks on the ground surface. When, therefore, a higher degree of finish is desired and the second stage operation is practiced, it is done 120 by means of a machine like that used in the first stage operation excepting that the member 17 is rotated at a lower speed than before, while the blade is reciprocated at a higher speed than before. Obviously, this 125 result may be accomplished by changing the pulleys on the same machine, or by using other machines, otherwise like the present machine but having a different drive ratio. The different relative movement produced 130

5 during the second stage operation results in causing the particles of abradant to move through paths crossing the paths through which they moved during the first stage operation. This eradicates the marks made during the first stage operation.

10 When a mirror-like finish is desired, the third stage operation is put in practice, similar machines being used with a third relative movement of blade and coating member, with a felt member in place of the wood member used in the first two stage operations, with a finer abradant than the emery used in the first two stage operations, and 15 with greatly reduced pressure. In the third stage operation, the rotating member has a higher speed than in either of the first two stage operations, while the blade is reciprocated at a slower speed than in either of the 20 first two stage operations.

25 It has been found that the best results are obtained, when a mirror-like finish is desired, by using the commercial product known as "4 F emery" as the floatative abradant in the first two stage operations; and by 30 using the commercial product known as "Chromotron" as the floatative abradant in the third stage operation.

35 Changes and variations may be made in the methods, apparatus, and machines, by means of which the invention is carried into effect. The invention, therefore, is not to be restricted to the precise details of the machine shown and described.

35 What is claimed is:

1. The method of, and apparatus for, grinding, as herein described, by causing particles of floatative abradant to be repeatedly embedded in ever-varying patterns in, 40 and washed out of, a soft non-abrasive medium movably contacting with a surface to be ground.

45 2. The method of grinding, which consists in forming a pool of liquid containing a modicum of floatative abradant, then submerging in said pool a surface to be ground and a relatively soft non-abrasive medium contacting with said surface, then producing a relative movement of said surface and 50 said medium to keep said liquid in motion and to cause particles of said abradant to be repeatedly caught in ever-varying patterns between said surface and said medium and embedded in said medium and alternately washed out of said medium.

55 3. The method of grinding, which consists in forming a pool of liquid containing a modicum of floatative abradant, then submerging in said pool a surface to be ground and a relatively soft non-abrasive medium 60 contacting with said surface under pressure which is predetermined in accordance with the nature of the finish desired, then producing a relative movement of said surface and said medium to keep said liquid in mo-

tion and to cause particles of said abradant to be repeatedly caught in ever-varying patterns between said surface and said medium and embedded in said medium and alternately washed out of said medium.

70 4. The method of grinding, which consists in forming a pool of liquid containing a modicum of floatative abradant, then submerging in said pool a surface to be ground and a relatively soft non-abrasive medium 75 contacting with said surface, then producing a relative movement of said surface and said medium which is the resultant of a reciprocating movement of said surface and a rotating movement of said medium to keep said liquid in motion and to cause particles of said abradant to be repeatedly caught in ever-varying patterns between said surface and said medium and embedded in said medium and alternately washed out of said 80 medium.

85 5. The method of grinding, which consists in forming a pool of water containing a modicum of floatative abradant of a fineness approximating that of chromotron, then submerging in said pool a surface to be ground and a relatively soft non-abrasive medium 90 contacting with said surface, then producing a relative movement of said surface and said medium to keep said water in motion and to cause particles of said abradant to be repeatedly caught in ever-varying patterns between said surface and said medium and embedded in said medium and alternately washed out of said 95 medium.

100 6. Means for grinding, comprising means for supporting a pool of liquid containing a modicum of floatative abradant, means for supporting an article with a surface to be ground submerged in said pool, a non-abrasive medium which is softer than and contacts with said surface, and means for producing a relative movement of said surface and said medium to keep said liquid in motion and to cause particles of said abradant to be repeatedly caught in ever-varying patterns between said surface and said medium and embedded in said medium and alternately washed out of said medium.

105 7. Means for grinding, comprising means for supporting a pool of liquid containing a modicum of floatative abradant, means for supporting an article with a surface to be ground submerged in said pool, a non-abrasive medium which is softer than and contacts with said surface, means for pressing said medium against said surface with a pressure which is predetermined in accordance with the nature of the finish desired, and means for producing a relative movement of said surface and said medium to keep said liquid in motion and to cause particles of said abradant to be repeatedly caught in ever-varying patterns between said surface and said medium and embedded 110

115

120

125

130

in said medium and alternately washed out of said medium.

8. Means for grinding, comprising means for supporting a pool of liquid containing a modicum of floatative abradant, means for supporting an article with a surface to be ground submerged in said pool, a non-abrasive medium which is softer than and contacts with said surface, and means for producing a relative movement of said surface and said medium which is the resultant of a reciprocating movement of said surface and a rotating movement of said medium to keep said liquid in motion and to cause particles of said abradant to be repeatedly caught in ever-varying patterns between said surface and said medium and embedded in said medium and alternately washed out of said medium.
9. Means for grinding, comprising means

for supporting a pool of liquid containing a modicum of floatative abradant, means for supporting an article with a surface to be ground submerged in said pool, a non-abrasive medium which is softer than and contacts with said surface, and means for producing a relative movement of said surface and said medium which is the resultant of a reciprocating movement of said surface and a relatively rapid rotating movement of said medium to keep said liquid in motion and to cause particles of said abradant to be repeatedly caught in ever-varying patterns between said surface and said medium and embedded in said medium and alternately washed out of said medium.

In testimony whereof, I have signed my name to this specification.

THOMAS C. SHEEHAN.
